The ornamental design for a stretchable can closure device, as shown and described.

DESCRIPTION

FIG. 1 is a side view of a stretchable can closure device depicted as attached to a can, showing our new design;
FIG. 2 is a top perspective view of the stretchable can closure device;

FIG. 3 is a bottom perspective view thereof;

FIG. 4 is a front view thereof;

FIG. 5 is a rear view thereof;

FIG. 6 is a left side view thereof with a right side view being a mirror image;

FIG. 7 is a top view thereof; and,

FIG. 8 is a bottom view thereof.

The broken line showing of a can in FIG. 1 is for the purpose of illustrating environmental structure and forms no part of the claimed design.
